PITCHER'S RUBBER

Paul S. Madsen, Bethany, Conn., assignor to The
Seamless Rubber Company, New Haven, Conn.,
a corporation of Connecticut

Application June 14, 1949, Serial No. 99,038

4 Claims. (Cl. 273—25)

1

This invention relates to pitchers' rubbers or plates used in playing the game of baseball.

The ordinary pitcher's rubber or plate in use at the present time consists of a slab or mat of elastic material, such as rubber, that is relatively thin and requires securing means engaging the same and the underlying earth for holding it in place. There are various objections to this form of slablike rubber, among which are the difficulty of providing satisfactory anchoring means, and the fact that the slab does not remain level but is likely to project upwardly at one or more edges owing to the action of dirt which works in under the margins of the slab.

One of the objects of the present invention is to overcome these drawbacks.

Another object is to provide a pitcher's rubber of simple form, in which there is effective provision for preventing dirt from working in under the rubber in the use of the article.

Another object is to provide a comparatively inexpensive form of improved rubber which can be effectively anchored in a manner such that the upper surface will remain flat and level.

In the accompanying drawing:

Fig. 1 is a perspective view of a pitcher's rubber embodying my improvements, showing it embedded in the ground and ready for use;

Fig. 2 is an enlarged end view of the article; Fig. 3 is a vertical transverse section showing a modified form; and

Figs. 4, 5 and 6 are vertical transverse sections showing, respectively, additional modified forms.

In the form of pitcher's rubber illustrated in Figs. 1 and 2, the rubber, instead of being in the form of a slab or plate lying in a single plane, is generally of block shape or billet shape, having, however, a cross-sectional shape which is open so as to provide a trough-like or channeled cross section. In this form the article has three planar outside surfaces all of the same area, namely, two side surfaces and an upper surface. This article is preferably made of rubber, although the term rubber is used in a broad rather than a restricted sense. The block is embedded in the earth so that, in the installed position, one of the planar elongated surfaces is flush or substantially flush with the surrounding earth. In Fig. 1 the block is shown as having what has been referred to as its upper or top surface flush with the surrounding earth.

In the drawing, the rubber is indicated generally at 10, and the surrounding earth at 11. The upper surface, which is flush with the surrounding earth, is indicated at 12 and the side

2

surfaces referred to at 13, each of these being in a plane perpendicular to the plane of the surface 12. The cross section of the block is such as to provide a channel, and in this particular case the channel is provided by forming in the rubber block at the under side a recess 14, which recess may have a rounded or curved shape or profile such as shown in the drawing. Conveniently this article can be made by molding a compound of rubber and other materials into the form shown, and vulcanizing, so as to provide a channeled member open at the bottom and having integral depending walls which in this case are curved at their inner surfaces, and at their upper parts provide in conjunction with the upper body a formation shaped like an arch.

This article when placed in the ground, as shown in Fig. 1, will have sufficient weight and stability to hold it in place while it is in use in playing the game of baseball, the upper flat surface remaining flush or substantially flush with the surrounding earth. While the article is preferably made of vulcanized rubber and has a certain amount of elasticity, it possesses sufficient rigidity and strength to enable it easily to support the weight of the player. This is true when the block is in the position shown in Fig. 1, and it is also true when and if the block is embedded so as to have either of the surfaces 13 uppermost. In the latter case, earth disposed in the channel will provide additional support for the part of the block which is uppermost, and if necessary, further or different interior support means can be provided.

It will be noted that, when the article is installed in the manner shown in Fig. 1, there is no possibility of dirt on or near the surface of the ground working in under the article in such a manner as to cause the rubber to become displaced or to cause the upper playing surface to be warped or distorted out of its flat planar condition. With the ordinary pitcher's slab, which is relatively thin and lies in a single plane, there is a great tendency for dirt to work in under the edge of the plate, and this is particularly true in respect to that edge of the plate which is located toward the home plate. This particular edge of the ordinary pitcher's plate not only becomes worn by the pitcher's shoes, but in making the pitch there is a great likelihood of the pitcher's foot, i. e., his initially advanced foot, in being lifted, throwing dirt against and under the forward edge. This is entirely obviated in the present instance by reason of the fact that the block shown has a forward wall depending

from the upper body and extending downwardly for a considerable distance, at any rate sufficient distance, into the earth.

In the event that either of the flat surfaces 13 is used as the top surface, it is obviously advisable to have the body or connecting portion of the channel member disposed toward the home plate, so that the conditions just referred to will be maintained in this adjustment. It will, of course, be apparent that with this structure three playing faces are provided on the block, and that when one of the faces becomes worn it is possible to turn the block so as to present a new face as the active face.

In the form shown in Fig. 3, the structure of the article is similar to that which has just been described. In this case, however, the channel, instead of being of arched shape, is of rectangular shape, the side walls 15 being of uniform thickness throughout their height, and the top wall 16 also being of uniform thickness. In this case it is preferred to employ an inner reinforcing member, and a wooden block 17 which fits within and fills the channel can be used advantageously for this purpose. It is preferred also to connect the channel member of rubber to the block so that the two will not be relatively displaced, and in this particular form the lower ends of the side walls are fastened to the lower part of the wooden block at intervals by suitable fasteners, illustrated as nails 18.

In the form shown in Fig. 4, the channel shape of the rubber block member is maintained, but in this case the side walls 19 are relatively short. They are, however, attached to the sides of the wooden block 20, as by fasteners illustrated as nails 21. In this case additional securing means are provided between the rubber member and the wooden block, and for this purpose the block is provided with a through bore 22 into which is frictionally driven a fastening pin 23 that is attached to the body of the rubber channel member. The connection between said body and the upper end of the pin 23 is provided by an internally threaded bushing 24 molded in place in the rubber member and engaged by external threads on the upper end of the pin.

In using the article of Fig. 4, it will be found that the front and rear walls of the channel member are projected downwardly into the earth sufficiently to inhibit the working of dirt under the channel member. In this particular case, also, the walls are fastened to the wooden block as a further means for preventing dirt from working in.

In the form shown in Fig. 5, certain principles previously mentioned or shown are retained. The rubber member again is a channel member, but the left-hand wall is longer than the right-hand wall. The structure is similar to that of Fig. 4, but the left-hand wall is continued downwardly across the side face of the wooden block, and is joined integrally to a short wall lying against the lower surface of the block. Here the left-hand wall is indicated at 25, and the short lower horizontal wall at 26. The upper wall 21 has a threaded insert 28 similar to the bushing or insert 24, and the wall 25 is provided with a similar insert 29, the arrangement being such that either of the inserts 28 and 29 is usable with the pin or dowel 30.

The form shown in Fig. 6 is similar to that shown in Fig. 5, but it will be apparent that in this case the extensions which are provided on

the main or full-width rubber walls of Fig. 5 are omitted.

It will be understood that the forms of Figs. 3, 5 and 6 are similar to the article of Fig. 2 in that when one of the playing faces becomes worn it is possible to turn the block so as to present a new face as the active face. In the form shown in Fig. 5, the block is a composite article comprising a wooden or like interior member and an outer cover member of rubber, the latter being usable in different adjustments upon the inner member which in this case is provided with holes or bores extending in one direction only. In other words, where the wooden block has vertical bores only, either of the full width side walls of the rubber member can be applied to the top surface of the wooden member. This same condition exists, of course, in the form of Fig. 6.

The rubber part of the article can be made readily by suitable methods known in the rubber industry and there is no limitation to any particular method of manufacture.

In respect to the forms shown in Figs. 4 to 6, inclusive, these have the further advantage that while they are very effective in preventing warping or distortion of the rubber member as a result of the penetration or lodgement of dirt or dust in the manner previously mentioned, the rubber part of the article can be used satisfactorily in connection with simple, easily procurable, interior supports such as elongated wooden members having a relatively small number of holes or sockets for receiving pins, dowels, or like fastening devices.

I do not claim broadly herein a pitcher's rubber having an upper wall presenting a flat playing surface and having a wall or body extending downwardly to prevent the ingress of dirt, nor do I claim broadly herein a pitcher's rubber comprising an elongated billet-like block adapted to be turned on its axis to present a fresh playing face, or other features claimed in my application, Serial No. 53,197, filed October 7, 1948.

Various changes may be made in the details of the structure without departing from the principles of the invention or the scope of the claims.

What I claim is:

1. A pitcher's rubber comprising an elongated member having an upper wall and a depending wall at right angles to the first wall adjacent the margin of the first wall, a supporting block for said member, and attaching means between said member and said block whereby the member is attached to the block in a predetermined position and is attachable in another position in which it is turned relatively to the block through a quarter turn.

2. A pitcher's rubber comprising an elongated member having an upper wall and a depending wall at right angles to the first wall adjacent the margin of the first wall, a supporting block for said member and attaching means between said member and said block whereby the member is attached to the block in a predetermined position and is attachable in another position in which it is turned relatively to the block through a quarter turn, said last-named means including screw sockets embedded in the respective walls and engageable with a screw member disposed in a bore of the block.

3. A pitcher's rubber comprising an elongated member having an upper wall and a depending wall at right angles to the first wall adjacent one margin of the first wall, a supporting block in the

75

angle between said walls having a fastener positioned in said block, and attaching means carried by said member and cooperable with said fastener whereby the member can be attached to the block in different angular adjustments.

4. A pitcher's mound having a ground cavity, a pitcher's rubber of block formation received in said cavity, said rubber comprising an elongated member having an upper wall constituting a playing face arranged flush with the ground, a depending wall adjacent the margin of the first wall and also constituting an additional playing face when arranged flush with the ground, a supporting block in the angle between said walls, and attaching means between said member and

15

said supporting block, whereby said additional playing face may be disposable in said cavity substantially flush with the ground by lifting the block formation, turning it on its axis, and lowering it.
